[57] CLAIM

The ornamental design for a connector for a wine rack or the like, as shown and described.

DESCRIPTION

FIG. 1 is a front elevational view of a connector for a wine rack or the like, showing my new design, the broken lines are for illustrative purposes only;

FIG. 2 is a perspective view;

FIG. 3 is a side elevational view, the opposite side being identical thereto;

FIG. 4 is a rear elevational view; and

FIG. 5 is a bottom plan view, the top being identical thereto.

FIGS. 2-5 have been drawn on an enlarged scale with respect to FIG. 1.

FIG. 1

FIG. 2

FIG. 3

FIG. 4

FIG. 5
